US0D1094004S

(12) **United States Design Patent** (10) **Patent No.:** **US D1,094,004 S**
(45) **Date of Patent:** **** Sep. 23, 2025**

(54) **PORTABLE BLENDER**

(71) Applicant: **E. Mishan & Sons, Inc.**, New York, NY (US)

(72) Inventors: **Mohan Rajasekaran**, Watertown, CT (US); **Steven Mishan**, New York, NY (US)

(73) Assignee: **E. MISHAN & SONS, INC.**, New York, NY (US)

(**) Term: **15 Years**

(21) Appl. No.: **29/956,910**

(22) Filed: **Aug. 9, 2024**

(57) **CLAIM**

The ornamental design for a portable blender as shown and described.

DESCRIPTION

FIG. 1 is a top, front perspective view of the portable blender showing of our design therefor;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines are shown for the purpose of illustrating parts of the portable blender that form no part of the claimed design.

1 Claim, 6 Drawing Sheets
